OVERHEAD TRACK FOR TROLLEYS.

SPECIFICATION forming part of Letters Patent No. 764,939, dated July 12, 1904.

Application filed April 7, 1904. Serial No. 201,662. (No model.)

To all whom it may concern:

Be it known that we, ALVIN J. GLOR and WILLIAM P. WEST, both of Varysburg, in the county of Wyoming and State of New York, 5 have invented a new and Improved Overhead Track for Trolleys, of which the following is a full, clear, and exact description.

Our invention relates to improvements in overhead tracks for trolleys, and particularly 10 to such tracks as are adapted to support various kinds of carriers.

The object of our invention is to produce a simple, inexpensive, and strong track which can be easily suspended, which is adapted to 15 safely carry a trolley and its load, and which has a simple and efficient switch mechanism by which the trolley and its load can be conveniently directed and which will operate also to stop the tracks at the open portions of the 20 switch, so that the trolleys thereon will not accidentally run off.

To these ends our invention consists of certain features of construction and combinations of parts, which will be hereinafter described 25 and claimed.

Reference is to be had to the accompanying drawings, forming part of this specification, in which similar figures of reference indicate corresponding parts in all the views.

30 Figure 1 is a perspective view of a portion of the track, showing particularly the switch mechanism. Fig. 2 is a broken side elevation of a part of the track and a hanger therefor. Fig. 3 is an end elevation of a hanger with 35 the track sides or slats attached thereto. Fig. 4 is a side elevation of a portion of the track, showing how the track is enabled to pass through a door. Fig. 5 is a plan view of the switch mechanism, and Fig. 6 is a cross-section 40 on the line 6-6 in Fig. 4.

In Fig. 1 we have for the sake of clearness omitted the stops for the several track-sections; but these are shown clearly in Fig. 5.

The track is made up of parallel strips or 45 slats 10, which are spaced apart by the blocks 11, to which the slats or strips are securely fastened by bolts 12 or equivalent fastening means. It will be noticed that the end por-

tions of two of the strips 10 overlap the spacing-blocks 11, but do not extend full length 50 of the blocks, so that in this way the strips of two sections of the track may be spaced at the abutting ends by the same block 11 and they can be supported, as described presently, by the same block. The blocks are carried 55 on hangers 13, which extend vertically through them and can be secured in any convenient way to some overhead support. The blocks 11 are provided near the ends and on opposite sides with projecting hook-shaped lugs, which 60 receive the strips 10 and which afford a secure support and also take the strain off the bolts 12.

For most purposes several of the tracks are used, and they converge to a switch 15, or rather they diverge from the switch, so that 65 a trolley can come down a single track and be guided by the switch-section 15 to any one of a series of tracks. The switch-rail 15 is made up like the parts already described and is hinged, as shown at 15^a, to a track-section. At its free end it is provided with a spacing-block 11 and has the side strip 10 projecting beyond the block, so that it can be dropped into the lugs 14 of any of the several 70 track-sections, as shown in Fig. 1. The free 75 end of the switch-rail is supported by the hanger 13^a, which is pivoted to one end of a lever 14, and the latter is arranged in a substantially horizontal manner and is fulcrumed, as shown at 16^b, in a link 16, which has a sleeve 80 16^a sliding on the bracket 18, which bracket is arranged above and adjacent to the several track-sections and is fastened to an overhead support.

The free end of the lever 14 has a depending handle 17, and the operator by pulling down on the handle tilts the lever 14 and lifts the free end of the switch-rail from the supporting-lugs 14 of the particular track-section with which the switch-rail is connected, and 90 then the operator by pushing or pulling laterally can cause the link 16 to slide along the bracket 18 till the free end of the switch-rail is opposite and a little above the particular track-section with which he wishes to connect 95 when the said free end is lowered and brought

into connection with the above-named track-section. To provide for closing the open track-sections, the switch-rail is provided with a transverse rod or bracket 20, having stops 21,

5 which are adapted to come opposite the several track-sections, as shown clearly in Figs. 4, 5, and 6. The stops 21 are adjustable on the rod 20, so that they can always be made to register with the several track-sections.

10 Thus when the switch-rail is connected with a certain track-section the stops will come opposite all the other sections, and any trolleys thereon will thus be prevented from accidentally running off.

15 Any suitable trolley can be run on the track, and in Fig. 3 we have shown in dotted lines a trolley which is suitable for the purpose. The track is also intended to run through doorways, and in order that it may not inter-

20 fere with the sliding doors we provide a swinging section 23, which is pivoted, as shown at 24, so that when it is engaged by the door it may swing upward, as shown by dotted lines in Fig. 4. To enable the door to open the

25 swinging section 23 automatically, we provide the door 25 with a cam 26, which when the door closes extends under the section 23 and automatically lifts it.

It will thus be seen that we provide a very 30 simple and inexpensive track which is adapted to any usual trolley or carrier and which can be easily suspended in any ordinary place.

Having thus fully described our invention, we claim as new and desire to secure by Letters Patent—

35 1. An overhead track comprising parallel side strips, a block arranged at the strip ends, said block serving to space the side strips apart and having a plural series of lugs or 40 hooks projecting from the sides to support

the side strips and to provide for holding the ends of two pairs of side strips, and a detachable hanger extending vertically through the block.

2. The combination with a series of track-sections having supporting-hooks at their ends, of a switch-rail having its free end adapted to rest in the hooks of the several track-sections, a bracket supported above the switch-rail and having a slide-bar extending 45 at essentially right angles to the direction of the track-sections, a link held to slide on the bracket, and a handle-lever pivoted in the link and having one end constructed to carry the switch-rail.

3. The combination with the track and a sliding door, of the vertically-swinging section in the track, and means as the cam-face on the door to raise the said section.

4. The combination with the track-sections 60 and the swinging switch-rail, of stops adjusted by the moving of the switch-rail and arranged to close the open ends of the track-sections which are not engaged by the switch-rail.

5. The combination with the several track-sections, of the switch-rail arranged to move into engagement with each of the said sections, and a series of stops carried by the switch-rail and adapted to close the track-sections which are not in engagement with the 70 switch-rail.

6. In an overhead track, the combination with the main track, of a vertically-swinging section, and means for swinging the said section by the movement of a door against it. 75
